D16905

UNITED STATES PATENT OFFICE.

CHARLES E. BULLARD, OF WORCESTER, MASSACHUSETTS.

DESIGN FOR A CARD.

SPECIFICATION forming part of Design No. 16,905, dated September 21, 1886.

Application filed June 14, 1886. Serial No. 205,152. Term of patent 3½ years.

To all whom it may concern:

Be it known that I, CHARLES E. BULLARD, a citizen of the United States, residing at Worcester, in the county of Worcester and State of Massachusetts, have invented and produced a new and original Design for Christmas and Birthday Cards and Similar Articles, of which the following is a specification, reference being had to the accompanying drawing, forming a part thereof, and which represents a face view of a card or art souvenir of my new design.

My design is for Christmas cards, birthday cards, or other similar articles; and it consists in certain novel features of the design thereof to produce a pleasing appearance, as will be hereinafter described.

In the drawings, the part marked A represents a card with the appearance of a sheet of paper, having a plane surface or face with a crease through its center, to be folded upon itself. Upon the upper half of the card A a raised panel or blank space is provided, suit-

able to receive a pictorial representation or illustration, B, and upon the lower half of the card a panel or blank space is provided, suitable to receive an illuminated text or motto, substantially as shown.

If preferred, the illustration B may be upon the lower half of the card A and the illuminated text or motto upon the upper half.

I claim—

The design for a Christmas card or other similar article, the same consisting of a plane surface or face having the appearance of a sheet of note paper, and provided with a raised panel upon its upper half having an illustration thereon, and having an illuminated text or motto upon its lower half, substantially as shown and described.

CHARLES E. BULLARD.
